HARRY B. GREEN, OF WOODBURY, NEW JERSEY, ASSIGNOR TO THE SPEED PRESS CO., OF CAMDEN, NEW JERSEY, A CORPORATION OF NEW JERSEY.

SHEET-FEEDING MECHANISM FOR PRINTING-PRESSES.

1,108,072.

Specification of Letters Patent. Patented Aug. 18, 1914.

Application filed August 4, 1911. Serial No. 642,343.

To all whom it may concern:

Be it known that I, HARRY B. GREEN, a citizen of the United States, residing at Woodbury, county of Gloucester, State of New Jersey, have invented a new and useful Sheet-Feeding Mechanism for Printing-Presses, of which the following is a specification.

My present invention in its broad and generic scope relates to mechanism for feeding sheets of any desired material, such as for example paper, into the proper position to be acted upon by other mechanism and while for purposes of illustration I have shown the same in conjunction with the printing roll of a printing mechanism it is apparent that its use is not limited to any specific type of mechanism.

One of the main objects of this invention is to devise a simplified and compact construction wherein the number of parts employed has been reduced to a minimum, with a consequent reduction in the cost of production and without in any way decreasing the efficiency of the sheet feeding mechanism.

A further object of my invention is to devise novel means for separating a sheet from a pile and guiding the same into operative position with respect to sheet clamping or other mechanism.

With the above, and other objects in view which will hereinafter appear in the detailed description, my invention in its broad scope consists of a novel sheet feeding and registering mechanism.

It further consists of a novel construction of and a novel manner of mounting a suction roll, and novel means for actuating the same.

It further consists of a novel construction of a suction roll adapted to contact with one of the sheets of a pile, novel means for reciprocating said suction roll and a novel construction of a tongue for guiding a sheet into operative relation with respect to a feed roller.

It further consists of a novel aligning mechanism and novel means for rendering the same inoperative.

It further consists of novel sheet clamping mechanism and novel means for controlling the same.

It further consists of novel means for causing a step by step elevation of the pile of sheets as a sheet is removed therefrom.

It further consists of other novel features of construction, all as will be hereinafter set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a portion of a machine showing my novel sheet feeding and registering mechanism as employed in conjunction therewith. Fig. 2 represents a side elevation of the assembled machine. Fig. 3 represents a sectional elevation of a portion of Fig. 1 but showing the suction roller and its adjuncts in a different relation with respect to the pile of sheets from that seen in Fig. 2. Fig. 4 represents a sectional elevation similar to Fig. 3 but showing the parts in a different relation to each other. Fig. 5 represents a plan view of the suction roller, the tongue and its adjuncts in detached position. Fig. 6 represents a sectional elevation of a portion of Fig. 1.

Similar numerals of reference indicate corresponding parts in the figures.

Referring to the drawings, 1 designates the frame of the machine in which is mounted a shaft 2, the latter being provided with a fly-wheel 3, and a ratchet wheel 4.

5 designates an arm having one end loosely mounted on the shaft 2 and provided with a spring actuated pawl 6, which is pivoted thereto and adapted to coact with the ratchet wheel 4, whereby a step by step movement of the shaft 2 is produced. The arm 5 has the outer end thereof pivoted to an arm 7 which is connected with a shaft 8 which latter is suitably journaled in the frame 1.

9 designates a sprocket wheel on the shaft 2 with which engages a sprocket chain 10.

the latter passing around a sprocket wheel 11 carried by a shaft 12 journaled in the frame 1. The sprocket chain 10 has connected therewith, in any desired manner, a bracket 13 which latter is connected with a table or support 14 on which the sheets are mounted, it being understood that an abutment is provided on one side of the table to prevent improper movement of the sheets in one direction while one or more standards 15 extend above the table 14 at the opposite edge thereof to prevent improper movement of the sheets, said standard being preferably beveled on its upper face, as indicated at 16. 17 designates a pawl coacting with the ratchet wheel 9 to prevent improper rearward movement thereof. On one side of the frame is located a rack 18 which is secured thereto by means of a fastening device 19, it being noted that the teeth of the rack 18 incline upwardly, the purpose of which will hereinafter appear in the description of the operation. The opposite side of the frame has secured thereto, in any desired manner, a wedge-shaped member 20. 21 designates a suction roller which is mounted in bars 22, a portion of said roller being adapted to roll on the wedge-shaped member 20, while the opposite side thereof is provided with a pinion 23 which engages with the teeth of the rack 18, as will be best understood by reference to Figs. 1 and 2. The suction roller 21 is provided with a discharge port 24 preferably centrally located therein and registering with a port 68 communicating with a suction hose 25 which, as seen in Fig. 2, is connected with the discharge port of any desired type of suction creating device such as a pump 26 and since any desired or conventional type of suction creating mechanism may be employed, I have deemed it unnecessary, in the present instance, to illustrate and describe in detail the construction thereof. 27 designates a piston rod which, in the present instance, for the purpose of illustrating one manner of operating the same, is provided with a roller 28 which travels in the cam groove 29 of a cam 30 mounted on a shaft 31 suitably journaled in the frame 1. 32 designates a bell crank lever fulcrumed at 33 in the frame 1 and provided with a roller 34 which is also adapted to travel in the cam groove 29, said bell crank lever 32 having pivoted thereto an arm 35, which is pivoted at 36 to one of the side bars 22, it being understood that, in the present instance, I preferably employ a plurality of cam members 30 and bell crank levers 32 and 60 their adjuncts and I have therefore deemed it unnecessary to describe in detail the construction of more than one of such members, since the same would involve needless repetition. The bars 22 as best seen in Figs. 1 and 52 2, are provided with the downward exten-

sions 37 in which is journaled an antifriction device consisting in the present instance of a roller 38.

39 designates arms or brackets carried by the frame and provided with the transversely extending bar 40 which serves as a support for the bars 22 during their reciprocation and also as a stop against which the roller 38 abuts to limit the forward movement of said bars 22. 75

41 designates a wedge-shaped cross bar or tongue the front face of which is downwardly inclined, as indicated at 42, it being noted that the front edge of the face 42 is located in proximity to the suction roller 21. 80

43 designates a guide plate which is journaled in the bars 22 and secured in its adjusted position by means of the set screws 44. 85

45 designates a series of pawls which are mounted on a shaft 46 journaled in the bars 22, said tongue 41 being preferably recessed in its rear face, as indicated at 47, in order to permit the pawl 45 to more closely approach said tongue. 90

48 designates an arm secured to the shaft 46 and against which the tension of a spring 49 is exerted to maintain the pawls 45 in engagement with the rear face of the tongue 41, it being seen that the top face of the tongue 41 is provided with recesses or cut-out portions 50, in order to provide for the passage of the clamping pawls 51 which are mounted on a shaft 52 and secured thereto by means of suitable fastening devices 53, said shaft 52 being carried by a cylinder 100 roller 54, a portion of the periphery of which is cut away, as indicated at 55. 95

56 designates a web or flange carried by the end of the cylinder roll 54, said web or flange 56 being broken away, as indicated at 105 57, to form a pawl releasing device. The shaft 52 has mounted thereon a block 58 having a slot 59 therethrough which is open on its outer face, whereby on the rotation of the cylinder 54, the walls of said slot will engage with the pins 60 and 61 which are provided for the proper control of the rocking pawls 51, it being understood that the number of said pawls preferably correspond to the number of recesses or cut-away portions 50. 110

62 designates a printing roll journaled in the frame 1 in any desired manner and adapted to print on the sheet carried by the cylinder roll 54. 115

63 designates feeding rolls for guiding the paper as it passes from the machine. 120

The cross bar or tongue 41 has its forward end rounded, as indicated by dotted lines at 64, in Fig. 5. The shaft 31 may be operatively connected with the roller of the printing shaft 62 in any desired manner and I have therefore deemed it unnecessary to show the connection and gearing since the same is well known in the art. 125 130

The operation of my novel device will now be readily apparent and is as follows: The sheets to be fed are piled on the table or support 14. Assuming that the parts 5 are in the position seen in Fig. 2 the rotation of the shaft 31 and thereby the cam 30 will cause the suction creating device 26 to be actuated and thereby create a suction on a sheet so that the top sheet of the pile will 10 be raised from the other sheets. Simultaneously therewith, owing to the provision of the elbow lever 32, the bars 22 will be moved forwardly thereby causing the inclined face 42 of the tongue 41 to pass beneath the top sheet and cause the same to be guided upwardly, as will be understood by reference to Fig. 3, so that the front edge of the sheet will engage the pawls 45 and will 15 be slightly bent upwardly, as indicated at 65, in Fig. 3. The clamping pawls 51 will now assume the position seen in Fig. 3 and on the further action of the machine the web or flange 57 will engage the pawl 48 and move the latter rearwardly thereby moving 20 the registering pawls 45 rearwardly so that the sheet of paper will pass to the clamping pawls 51 and owing to the curved inner face thereof will be guided into the position seen 25 in Fig. 4, so that the paper will be clamped 30 between the clamping pawls 51 and the shoulder 66, as seen in Fig. 4, it being understood that the action of the suction in lifting the papers is only at the beginning of the forward movement of the tongue 41, 35 since the pinion 23 coacting with the ratchet 18, will cause the suction roller 21, during the forward feed of the tongue to be rotated and also gradually raised, so that the suction roller 21 is gradually moved away from 40 the sheet. On the further actuation of the machine the sheet of material which is now clamped relatively to the cylinder 54 will be rotated in unison with such cylinder so that 45 in the embodiment illustrated the sheet will be brought in proper position to coöperate with the printing roll and receive any desired indicating data. As soon as the cylinder roll is rotated sufficiently for the slot 50 59 to coact with the pin 60, the clamping or gripping pawls 51 will be moved out of engagement with the shoulder 66 so that the paper will be released and passed between the feeding rolls 63 and thence to a desired 55 place of utilization. It will be seen that after a sheet of material has been fed from the pile, the connecting arms 5 and 7 operatively connected with the shaft 8 on which the cylinder 54 is mounted, will cause the sprocket chain 10 to raise the table or 60 support 14 so that the upper sheet of the pile is always maintained in the proper position relatively to the suction roll 21 and the tongue 41, so that the operation will be the same irrespective of the number of sheets 65 carried by the table or support 14. On the

continued operation of the machine, the tongue 41 and its adjuncts will be moved rearwardly into the position seen in Fig. 2, and the slot 59 coacting with the pin 61 will cause the clamping or gripping pawls 51 to be brought again into the position seen in Figs. 3 and 4 at the proper time and the cycle of operation will be completed. It will be seen that as the flange 56 moves out of engagement with the pawl 48, the spring 49 will cause the registering or positioning pawls 45 to return to their normal position such as is seen in Figs. 1 and 2.

Special attention is directed to the novel movement of the suction roll and the tongue 41, since it will be seen that instead of reciprocating the same in a plane parallel to the table 14 it is reciprocated at an angle thereto so that the tongue 41 will rest on the pile of sheets and prevent their improper movement during the separating, registering and feeding operation. It will also be seen that in my present invention I provide a combined feeding and registering device, the wedge-shaped tongue serving to move a sheet upwardly into proper position relatively to the cylinder, and the pawls 45 serving to register and position the paper so that the same will be accurately positioned relatively to the cylinder 54 and the clamping or gripping pawls 51.

It will now be apparent that I have devised a novel and useful construction of a sheet feeding mechanism for printing presses which embodies the features of advantage 100 enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of 105 its advantages.

Having thus described my invention, what I claim as new and desire to secure by Letters Patent, is:—

1. In a sheet feeding mechanism adapted to feed sheets to a cylinder roll, a sheet support, a suction roll, devices on which said roll is mounted for feeding the separated sheets, and serving to support the sheet during substantially the entire passage 115 thereof from the sheet support to the cylinder roll, said devices being incapable of movement independent of said suction roll, means for reciprocating said devices and thereby the suction roll, means independent 120 of the suction roll for maintaining the top sheet of the support at a uniform height irrespective of the number of sheets on said support, and means for rotating said suction roll during its reciprocating movement. 125

2. In a sheet feeding mechanism adapted to feed sheets to a cylinder roll, a sheet support, a suction roll, a wedge-shaped tongue mounted in rear of said suction roll and connected therewith and beneath which and the latter a sheet is fed, the inclined face of said tongue extending from the suction roll to substantially the face of the cylinder roll, devices for creating a suction in said roll, and means for reciprocating said tongue and thereby said roll in a rectilinear plane extending at an angle to the normal plane of the sheets and said tongue being incapable of movement independent of said suction roll.
3. In a sheet feeding mechanism adapted to feed sheets to a cylinder roll, a sheet support, means for elevating the same step by step, a wedge-shaped tongue serving to support the sheet during substantially the entire passage thereof from the sheet support to the cylinder, a suction roll connected and moving in unison therewith, and incapable of movement independent of said tongue, devices for reciprocating said tongue and thereby said roll, in a rectilinear plane extending at an angle to the normal plane of the sheets, and means coacting with said roll during its reciprocation to cause rotation thereof.
4. In a sheet feeding mechanism, a sheet support, a reciprocable frame, a wedge-shaped tongue carried by said frame, a suction roll mounted in said frame in proximity to said tongue, a pinion carried by one end of said roll, a wedge-shaped support with which the other end of said roll engages, a rack having its teeth extending in a plane at an angle to the plane of the sheets and with which said pinion engages, means for creating a suction in said roll, and devices for reciprocating said frame to feed the separated sheet of paper from said support.
5. In a sheet feeding mechanism, a sheet support, a reciprocable frame, a wedge-shaped tongue carried by said frame, a suction roll mounted in said frame in proximity to said tongue, a pinion carried by said roll, a rack having its teeth extending in a plane at an angle to the plane of the sheets and with which said pinion engages, means for creating a suction in said roll, devices for reciprocating said frame to feed the separated sheet of paper from said support, and means for elevating said support to maintain the top sheet of the pile at a uniform height.
6. In a sheet feeding mechanism, a sheet support, means for intermittently elevating said support, a frame, a wedge-shaped tongue mounted therein, a suction roll mounted in said frame in proximity to said tongue, a guide carried by said frame, positioning pawls carried by said frame and serving as a stop for the sheet being fed, means for reciprocating said frame, devices coacting with said pawls during their reciprocation to release the latter, and means for causing the rotation of the suction roll during the reciprocation of the frame.
7. In a sheet feeding mechanism, a sheet support, means for elevating said support, a frame adapted to reciprocate at an angle to said support, a wedge-shaped tongue carried by said frame and having its forward edge rounded, a suction roll carried by said frame, means for reciprocating said frame, devices for causing the rotation of said roll during the reciprocation of said frame, suction creating mechanism communicating with said roll, and means carried by said frame for positioning the paper when said frame reaches the limit of its forward movement.
8. In a sheet feeding mechanism, a support, means for causing a step by step elevation of said support, a frame, a wedge-shaped tongue carried thereby, a suction roll mounted in said frame in advance of said tongue, suction creating mechanism connected with said roll, devices for rotating said roll during its reciprocation, means for reciprocating said frame at an angle to the support to cause said tongue to prevent improper movement of the sheets, a shaft mounted in said frame, pawls carried thereby, an arm fixed on said shaft, yielding means coacting with said arm for maintaining said pawls in the path of a sheet, and devices for automatically releasing said pawls at predetermined times.
9. In a sheet feeding mechanism, a support, means for causing a step by step elevation of said support as a sheet is removed therefrom, a frame supported at an angle to said support, a wedge-shaped tongue carried thereby, a suction roll mounted in advance of said tongue, devices for rotating said roll during the reciprocation of said frame, a shaft mounted in said frame, positioning pawls carried thereby, an arm mounted on said shaft, yielding means coacting with said arm to maintain said pawls in the path of a sheet, a sheet receiving mechanism, devices carried thereby and coacting with said arm to release said pawls, means for clamping a sheet to said mechanism, and devices for reciprocating said frame and for actuating the clamping mechanism.
10. In a sheet feeding mechanism, a sheet support, means for causing a step by step elevation of said support upon the removal therefrom of a sheet, a reciprocating frame adapted to travel at an angle to the horizontal plane of said support, a suction roll carried by said frame, means common to said roll and said frame for causing the rotation of the latter, devices carried by said frame for guiding a separated sheet, positioning devices carried by said frame and

normally in the path of a sheet, means for moving said positioning devices out of the normal path of a sheet, and devices for reciprocating said frame.

- 5 11. In a sheet feeding mechanism, a sheet support, means for causing a step by step elevation of said support, a frame mounted in proximity thereto and comprising side members, and an anti-friction device connecting said members, a wedge-shaped tongue carried by said frame near one end, a suction roll rotatably mounted in the frame in proximity to said tongue, a stop coacting with said anti-friction device to limit the forward movement of said frame, a suction creating device connected with said roll, and means for reciprocating said frame in a plane at an angle to the horizontal plane of the sheet support.
- 10 12. In a sheet feeding mechanism, a sheet support, a frame, a wedge-shaped tongue carried by said frame, a suction roll carried by said frame, means for causing relative movement of said frame and said sheet support, devices for rotating said suction roll, suction creating mechanism communicating with said suction roll, and positioning devices movably situated at the upper end of said wedge-shaped tongue to serve as a temporary stop for the separated sheet.
- 15 13. In a sheet feeding mechanism, a sheet support, a frame, a wedge-shaped tongue carried by said frame, a suction roll carried by said frame, means for causing relative movement of said frame and said sheet support, devices for rotating said suction roll, suction creating mechanism communicating with said suction roll, means for positioning the sheet when said frame reaches the limit 20 of its forward travel, and guiding mechanism carried by said frame to direct the sheet into engagement with said positioning means.
- 25 14. In a sheet feeding mechanism, a sheet support, a frame, a wedge-shaped tongue carried by said frame, a suction roll carried

by said frame, means for causing relative movement of said frame and said sheet support, devices for rotating said suction roll, suction creating mechanism communicating with said suction roll, means for positioning the sheet when said frame reaches the limit of its forward travel, and guiding mechanism adjustably carried by said frame and terminating in proximity to said suction roll for guiding the sheet into contact with said positioning means.

30 15. In a sheet feeding mechanism, a sheet support, a frame, a wedge-shaped tongue carried by said frame, a suction roll carried by said frame, means for causing relative movement of said frame and said sheet support, devices for rotating said suction roll, suction creating mechanism communicating with said suction roll, means for positioning the sheet when said frame reaches the limit of its forward travel, guiding mechanism adjustably carried by said frame, terminating in proximity to said suction roll for guiding the sheet into contact with said 35 positioning means, and means for causing a step by step elevation of said support as the sheets are removed therefrom.

40 16. In a sheet feeding mechanism adapted to feed sheets to a cylinder roll, a sheet support, a wedge-shaped member serving to support the sheet during substantially the entire passage thereof from the sheet support to the cylinder roll, a suction roll connected and moving in unison with said member, and incapable of movement independent of said member, means for reciprocating said member and thereby the suction roll, and a guiding device situated at a suitable point with respect to the wedge-shaped face 45 of said member for properly guiding the sheet thereon.
